UNITED STATES PATENT OFFICE.

JOSEPH M. KREITZER, OF BRIGGSDALE, COLORADO.

OPERATING-TABLE.

1,117,403.

Specification of Letters Patent. Patented Nov. 17, 1914.

Application filed July 2, 1913. Serial No. 777,008.

To all whom it may concern:

Be it known that I, JOSEPH M. KREITZER, a citizen of the United States, residing at Briggsdale, in the county of Weld and State 5 of Colorado, have invented certain new and useful Improvements in Operating-Tables, of which the following is a specification.

My invention relates to improvements in 10 operating tables for use of surgeons, osteopaths and others in the treatment of diseases, fractures or deformity of parts of the human body by manual or mechanical operations.

The primary object of my invention is to 15 produce a table which is constructed to provide a wide range of adjustments for the proper support of a body in the postures best adapted for the treatment of the peculiar disorder for which it is operated upon.

Another object of my invention resides in 20 providing in connection with the table, a device whereby a body reclining thereon, may be stretched for the correction of displacement of the vertebrae of the spine or other defective positions of the joints, and in designing the different parts of which the 25 table is composed, it has been my purpose to combine cheapness of construction with ease of adjustment and general practicability in use.

I attain the above stated objects by the 30 mechanism illustrated in the accompanying drawings in the various views of which like parts are similarly designated, and in which,

Figure 1 represents a side elevation of my 35 improved operating table with its adjustable parts in their normal position, Fig. 2, a similar elevation showing the adjustable parts of the table in one of their adjusted positions, in full lines and in other positions 40 in broken lines, Fig. 3, a transverse section taken along the line 3—3, Fig. 1 drawn to an enlarged scale, Figs. 4 and 5, fragmentary side elevations of the middle portion of the table showing two different positions of the 45 middle section of its top, Fig. 6, a plan view of the lower member of the double foot-end section of the table showing the relative position of the stretching device included in my invention, Fig. 7, a plan view of the 50 head-end section of the table, and Fig. 8, a section taken along the line 8—8, Fig. 1, looking upwardly in the direction of the arrow drawn across the line.

My improved table consists of a supporting structure 2 and a top 3 which is composed of three adjustable sections which in the following description will be referred to as the head-end section 4, the middle or intermediate section 5, and the foot-end section 6.

The supporting structure consists of two transverse frames each composed of two legs 7 which at their upper ends are connected by sharp-edged cross-bars 8 to which the sections of the top are pivotally connected.

The frames are steadied by braces 9 which extend slantingly from the upper ends of their legs, and they are connected by two side rails 10 which at the foot-end of the structure are bent downwardly to engage the surface upon which the same is supported and thereby increase the stability of the device. The braces 9 of the frame at the head-end of the table are notched along their upper edges for the support of the corresponding section of the top of the table, as will hereinafter be more fully described.

The portions of the side rails extending 80 between the two transverse frames are notched in their upper edges to support the middle section of the top in its adjusted positions and the rigidity of the supporting structure may be increased by means of two cross-pieces 12 which at their ends are attached to the side rails adjacent the frames.

The head-end section of the top which in practice supports the head of the patient, is composed of an upholstered leaf which has a central opening 13 to receive the face of 90 the patient when the nature of the operation requires him to lie face downward on the table. The section is hinged at its rearward end to the cross-bar 8 of the adjacent end so as to be movable either up or downwardly, 95 and it is supported in its adjusted positions by means of a pair of connected pawls or props 14 which are hinged at their upper ends at the under side of the leaf and which are sharpened at their opposite extremities 100 to engage the notches of the slanting braces 9 which as hereinbefore described, form part of the frame to which the section is attached. The props 14 are furthermore connected with the leaf by means of coiled 105 springs 15 which facilitate their adjustment

and aid in maintaining the parts in their adjusted positions.

The intermediate section 5 is composed of three upholstered leaves which are joined 5 along their adjacent edges by hinge connections to move in opposite directions. The end leaf of the middle section nearest the head end of the table is pivotally connected by means of hinges to the cross-bar 8 of the 10 frame at its side opposite to that at which the head-end section is attached, and the opposite end-leaf of the section adjacent the foot-end of the table is provided with connected supporting pawls or props 16 which 15 are attached thereto by hinges at its under side, and which are sharpened at their free extremities to support the section in different positions by engagement with the notches in the upper edges of the side rails of the 20 supporting structure.

By adjustment of the three leaves of the section about their connecting hinges, they 25 may be positioned in angular relation to each other to provide either a convex or concave support for a body reclining on the top of the table, and the relative positions of the leaves may furthermore be varied in accordance with different requirements by maintaining two of the adjoining leaves 30 in their normal aligned positions and placing them at an angle to the third leaf as shown in Fig. 4, or by placing all the leaves in angular relation to each other as has been indicated in Fig. 5.

35 To maintain the leaves of the middle section in their several relative adjusted positions, I have provided a mechanism which consists of a brace 17 which at one of its ends is pivotally and laterally adjustably mounted 40 on a lug 18 secured at the under surface of the end-leaf of the section to which the connected props 16 are attached, and which at its opposite end has a transverse stop 19 which serves to prevent its longitudinal displacement by engagement with a U-shaped hanger 20 which is pivotally suspended 45 from the opposite end-leaf of the section.

The middle leaf of the section has at its 50 under surface two cleats 21 and 22 of different heights which are placed side by side to engage the brace in two of its adjusted positions.

55 The brace 17 extends between the downwardly extending members of the hanger so that its transverse stop may engage with either. One of the said members has in its inner edge, two notches 23 and 24 to provide seats at different distances from the under surface of the leaf to receive the end 60 of the brace, and the other member has opposite to the lower one of said seats, a similar notch 25 which is provided for the same purpose.

When the leaves of the middle section are 65 in their normal aligned position as shown in

Fig. 1 of the drawings, the brace resting in the upper notch 23 engages the lower surfaces of the three leaves and thereby supports them against downward deflection.

When the leaves are adjusted to provide an arched support for the body, as is illustrated in Fig. 2, the brace is moved laterally to engage the lowest cleat 22 and is supported in the notch 25 of the hanger, the engagement of its cross piece 19 with the 70 member of the hanger in which the said notch is formed, holding it against longitudinal displacement.

When the leaves are deflected to provide a hollow or concave support for the body, 80 they may be placed in either of the two positions shown in Figs. 4 and 5. In one of these positions (that illustrated in Fig. 4) two of the leaves are placed in alignment at an angle to the third leaf, and the brace 17 85 which engages the lower surfaces of the aligned parts, rests in the notch 24 of the hanger. In the other adjustment of the middle section of the table, the three leaves extend in angular relation to each other as 90 shown in Fig. 5, and the brace placed in engagement with the lower oblique surface of the cleat 21, rests upon the cross-piece at the lower end of the hanger.

The foot-end section of the table top consists of two members 26 and 27 which at 95 one of their ends are movably connected by means of hinges 28, and one of which rests normally upon the other, as shown in Fig. 1.

The lower section consists of a frame which as best shown in Fig. 6, is composed of side and cross-bars and which at its end adjacent the middle section is joined to the cross-bar 8 of the adjacent frame of the supporting structure by hinge-connections 100 105 which permit of its being moved either up or downwardly.

The upper member 27 of the foot-end section consists of an upholstered leaf which 110 may be held in any of a number of predetermined angular positions with relation to the lower member by means of a jointed prop 29, the hinged parts of which are yieldingly held in alignment by means of springs 30 which permit of their being 115 placed in angular relation to each other, as is shown in Fig. 2.

The prop as shown in the drawings is composed of three parts and consequently is adapted to hold the upper member of the 120 section at three different angles with relation to the lower section of the same.

The foot-end section is in its entirety supported at its end opposite to that at which it is attached to the cross-bar 8, upon connected, jointed uprights 31 which at their lower ends are pivotally mounted between the ends of the side rails of the supporting structure.

The uprights are composed of two parts 130

which are joined by hinge connections as at 32 and normally maintained in alinement by means of springs 33 which are adapted to permit the upper parts of the uprights to be folded upon their lower ones, for the purpose of supporting the section in a downwardly slanting position as is indicated in Fig. 2 in broken lines.

From the above description it will be seen that my improved table may be readily adjusted to any position required for the comfort and relief of the patient, or to facilitate manipulation or operation upon affected parts of the body, by placing them within easy reach of the operator.

While the precise form of the sections of which the table top is composed is not material in adapting them for the principal purposes for which they are provided, I preferably make the foot-end section of greater width than the head-end section and taper the intermediate section to correspond at its ends with the outer sections, as is shown in Fig. 8 of the drawings.

The stretching device which is applied to the table for the purpose of extending a body reclining thereon, consists of a U-shaped metal frame 34 which is slidingly mounted in bearings 35 between the side bars of the lower member 26 of the foot-end section.

The cross-bar of the frame which extends beyond the foot-end of the table has two depressions 36 adapted to receive, in practice, the ankles of a patient reclining on the table. The depressions are preferably padded to prevent possible injury, and suitable straps 37 are provided to secure the legs of the patient to the cross-piece, as is required in the stretching operation.

A rock shaft 38 mounted in bearings on the part 26 of the foot-end section, has a pair of parallel arms 39 which by means of rods 40 are operatively connected with the adjacent extremities of the side members of the U-shaped frame, and an arm 41 formed at an extremity of the shaft in angular relation to the other arms, is by means of a rod 42 connected with a treadle 44 which is pivotally mounted on the adjacent side rail of the supporting structure.

A rack bar 43 secured to the leg of the table past which the treadle extends, serves to secure the latter in its adjusted positions.

In the use of the stretching appliance, the upper portion of the patient's body is by means of a suitable harness, secured at the head end of the table which to this end has been provided with fastening devices such as the hooks 46 shown in the drawings.

The legs of the patient which engage the padded portions of the cross-piece of the sliding frame 34, are secured thereto by the before-mentioned straps 37, and the body is stretched to any desired degree by down-

ward pressure on the treadle which through the instrumentality of the rock shaft, causes the frame to which the legs of the patient are attached to slide outwardly.

The harness which secures the upper portion of the body may be of any suitable design to secure the head, shoulders or arms of the patient, and inasmuch as its exact design or construction does not form part of the present invention, only its ends at which it is attached to the table have been shown in the drawings at 45.

It will be understood that by moving the support 31 about its pivots by which it is connected to the side rails 2, the foot-end section of the table can be let down to the floor and that modifications in the arrangement and construction of the parts of my improved table may be resorted to within the scope of my invention as set forth in the following claims.

I claim:

1. In a table of the character described, a supporting structure, and a sectional top including a section composed of a plurality of leaves pivotally connected at adjoining edges, an adjustable brace normally engaging said leaves for holding them in alinement, and a member providing a plurality of supports for said brace to maintain said leaves in angular relation to each other.

2. In a table of the character described, a supporting structure, and a sectional top including a section composed of a plurality of pivotally connected leaves, an adjustable brace normally engaging said leaves for holding them in alinement, a member providing a plurality of supports for said brace for maintaining said leaves in angular relation to each other, and cleats on said section for engagement with said brace.

3. In a table of the character described, a supporting structure, and a sectional top including a section composed of three pivotally connected leaves, a brace adjustably attached to one of the outer leaves, a member connected with the other outer leaf, having a plurality of supports for holding said brace in different adjusted positions, and cleats on the middle leaf for engagement with said brace.

4. In a table of the character described, a supporting structure and a sectional top including a section composed of two pivotally connected members, one of which rests normally upon the other, a sliding frame on the lower one of said members, adapted for the attachment of an extremity of a person reclining on said top, and means on said structure for imparting a sliding movement to said frame.

5. In a table of the character described, a supporting structure and a sectional top including a section composed of two pivotally connected members, one of which rests

normally upon the other, a stretching device operatively mounted on the lower one of said members, and adapted for the attachment of an extremity of a person reclining on said top, and means on said structure for the operation of said device.

6. In a table of the character described, a supporting structure and a sectional top including a section composed of two pivotally connected members, one of which rests normally upon the other, a sliding frame on the lower one of said members, adapted for the attachment of an extremity of a person reclining on said top, a rock shaft connected with said frame for imparting a sliding movement thereto, and a treadle connected for rotation of said shaft.

7. In a table of the character described, a supporting structure, and a top composed of three normally aligned sections, one of the end sections being composed of two pivotally connected, relatively adjustable parts, and the middle section being separately adjustable to provide a rigid, curved support.

25 8. In a table of the character described, a supporting structure, and a top comprising a foot-end section, a head-end section and a normally straight intermediate section adapted for adjustment to provide a rigid arched support of more than two sides.

35 9. In a table of the character described, a supporting structure, and a top comprising a foot-end section, a head-end section, and a normally straight intermediate section adapted for adjustment to provide a rigid arched support of either two or more sides.

10. In a table of the character described, a supporting structure, and a top comprising a foot-end section, a head-end section, and a normally straight intermediate section adapted for adjustment to provide a concavity of a plurality of rigidly held sides.

45 11. In a table of the character described, a supporting structure, and a top comprising a foot-end section, a head end section and a normally straight intermediate section adapted for adjustment to provide a concavity of either two or more rigidly held angularly disposed surfaces

50 12. In a table of the character described, a supporting structure, and a top comprising a foot-end section, a head-end section and a normally straight intermediate section adapted for adjustment to provide either a rigid arched support or a concavity.

13. In a table of the character described, a supporting structure, and a top comprising a foot-end section, a head-end section and a normally straight intermediate section adapted for adjustment to provide a rigid arched support of either two or more sides, or a concavity of either two or more rigidly held angularly disposed surfaces.

65 14. In a table of the character described

a supporting structure and a top comprising three normally aligned sections, which are separately adjustable to different angles, the intermediate section being adapted for adjustment to provide a rigid, curved support.

70 15. In a table of the character described, a supporting structure and a top comprising three normally aligned sections which are separately adjustable to different angles, the intermediate section being adapted for adjustment to provide a rigid curved support and one of the end sections being composed of two pivotally connected, relatively adjustable parts.

75 16. In a table of the character described, a supporting structure, and a sectional top including a normally straight section which is separately adjustable in its entirety to different angular positions and which is adapted for adjustment to provide a rigid, curved support.

80 17. In a table of the character described, a supporting structure, and a top comprising a foot-end section, a head end section and an intermediate section pivoted at one of its ends and composed of a plurality of pivotally connected leaves, and adjustable means for holding said leaves in angular relation to each other whereby to provide a rigid, curved support.

85 90 18. In a table of the character described, a supporting structure, and a top comprising a foot-end section, a head end section and an intermediate section pivoted at one of its ends and composed of a plurality of pivotally connected leaves, means for adjusting said intermediate section in its entirety to different angular positions, and adjustable means for holding said leaves in angular relation to each other whereby to provide a rigid, curved support.

95 19. In a table of the character described, a supporting structure and a sectional top including a normally straight intermediate section separately adjustable to provide a rigid, curved support.

100 20. In a table of the character described, a supporting structure, and a sectional top including a section adapted for adjustment to be placed in either an arched position or to provide a concavity between the other sections.

105 21. In a table of the character described, a supporting structure, and a sectional top including a pivoted foot-end section adapted to be adjusted in its entirety to an angular position below the plane of the other sections and which is composed of two pivotally connected members one of which rests normally upon the other and is adjustable to different angles with relation thereto.

110 120 22. In a table of the character described, a supporting structure, and a sectional top including a head-end section having an opening adapted to receive the face of a

patient reclining face downward on the said top.

23. In a table of the character described, a supporting structure and a top composed of two end sections and an intermediate section which is adapted to be placed in an arched position.

In testimony whereof I have affixed my signature in presence of two witnesses.

JOSEPH M. KREITZER.
